UNITED STATES PATENT OFFICE.

CHARLES H. OSBORNE, OF FORESTVILLE, CONNECTICUT, ASSIGNOR OF TWO-
THIRDS TO FRED. G. STEVENSON AND ABRAM W. OSBORNE, BOTH OF
SAME PLACE.

FOUNTAIN-BRUSH.

SPECIFICATION forming part of Letters Patent No. 371,899, dated October 18, 1887.

Application filed April 11, 1887. Serial No. 234,358. (No model.)

To all whom it may concern:

Be it known that I, CHARLES H. OSBORNE, a citizen of the United States, residing at Forestville, in the county of Hartford and State 5 of Connecticut, have invented certain new and useful Improvements in Fountain-Brushes, of which the following is a specification.

My invention relates to improvements in fountain-brushes; and the objects of my improvements are efficiency in operation, convenience in use, and economy of construction.

In the accompanying drawings, Figure 1 is a central longitudinal section, partly in elevation, of my brush complete. Fig. 2 is a detached view of a different form of brush-head adapted for use with my improvement, and Fig. 3 is a transverse section thereof on line x x, Fig. 2.

All of the parts shown in Fig. 1, except the 20 yoke a, are of a circular form in cross section, and therefore the single view is deemed sufficient.

A designates the handle, which is made hollow to form a reservoir, B, and preferably 25 of glass, so that the user can readily see when the supply of fluid blacking is exhausted.

C is the upper collar, screw-threaded on its interior for the reception of the threaded cap D.

E is the lower collar, also interiorly threaded 30 for the insertion of the brush-head F. This particular form of brush-head is adapted for use as a stencil-brush. When the handle A, having reservoir B, is made of glass, the collars C and E may be attached thereto in any 35 ordinary manner of securing collars on glass, as, for instance, by cement.

The cap D is provided with an inwardly-projecting hub, at the lower end of which is formed a valve-seat for the valve b. The valve- 40 stem c projects outwardly through the hub of the cap and terminates in a suitable knob or push-button, d. A spiral spring, e, surrounds the valve-stem and exerts a constant pressure in a direction to close the valve. The yoke a is

45 in the form of a strap extending down from the hub to form a bearing for the upper end of the connecting-rod f. The lower collar, E, is provided with a like hub, valve-seat, valve b', valve-stem c', spring e', and knob d', into the

latter of which the lower end of the connecting-rod is secured. This connecting-rod is disconnected from the valve b, so as to allow the respective springs of both valves to act independently and better hold the valves closed than could be the case if both valves were rigidly secured to said rod. The upper end of the rod f, however, comes close to the under side of the valve b, so that it will be depressed in opening the said valve.

The brush-head F is provided with a central 50 tube, g, which extends down into the middle of the bristles or fibers of the brush-head, as shown. The upper end of said tube extends upwardly and surrounds the valve b'.

In use the reservoir will be supplied with a 55 blacking or marking fluid. When it is desired to feed the same to the brush, it is only necessary to depress the push-button d, thereby opening the valve b to let in air. The valve b striking on the upper end of the connecting- 60 rod f will, by its continued movement, also open the valve b' to let the fluid flow to the brush-head. Releasing the push-button d will permit the springs to close both valves.

Instead of a brush-head with a central feed 75 a brush-head with a surface-feed may be desirable, especially for small brushes, as a marking-brush. Such a head is shown in Figs. 2 and 3, and it is adapted to be screwed into the same handle, as in Fig. 1. The lower end of 80 its tube h is slotted longitudinally, as at k, so as to let the fluid run from the tube down on the exterior of the brush fibers. I do not wish to confine myself to the details of construction, but illustrate and describe this brush-head, 85 Figs. 2 and 3, as one form of a surface-feeding brush-head that may be used in connection with my fountain or reservoir.

I do not claim, broadly, a fountain-brush provided with an outlet-valve, as several 90 brushes of this character are shown in the prior art; neither do I claim, broadly, an outlet and inlet valve.

I claim as my invention—

1. The herein-described fountain-brush having a fixed brush-head and a reservoir provided with outlet and inlet valves at the bottom and top adapted to move independently 95

of said brush-head, and a connecting-rod between said valves, substantially as described, and for the purpose specified.

2. The combination of the reservoir, a brush-head, the spring-pressed valve for opening and closing the passage between said reservoir and brush-head, the spring-pressed valve for admission of air, and the connecting-rod *f*, said valves and rod being located in align-

ment, but with the rod disconnected from one of said valves, whereby the respective springs act independently upon said valves in holding them in their closed position, substantially as described.

CHARLES H. OSBORNE.
